UNITED STATES PATENT OFFICE.

AUGUSTUS M. SOSA AND HANS BAERBALCK, OF CINCINNATI, OHIO, ASSIGNEES TO THE AMERICAN TOOL WORKS COMPANY, OF CINCINNATI, OHIO, A CORPORATION OF OHIO.

LUBRICATING DEVICE.

Application filed December 2, 1926. Serial No. 152,130.

Our invention relates to lubricating devices, and is exemplified as applied to a so-called metal shaping machine, although our invention is applicable to other metal working machines, in which the combinations set forth in the claims may be employed.

In this exemplification there is a ram arranged to be operated by a rocker-arm pivoted at a lower portion and having articulating 10 connection with the ram at an upper portion, a crank being arranged to reciprocate the rocker-arm.

It is the object of our invention, to provide a plurality of lubricant feeding reservoirs, and a plurality of lubricant collecting 15 reservoirs, a portion of which serves for both collecting and feeding the lubricant, arranged in novel manner so that the respective reservoirs lubricate the bearings at different parts 20 of the machine, and so that lubricant overflows from one reservoir to the other and is returned to the primary reservoir for reuse; and, further, to provide a lubricant feeding reservoir with novel filtering means so that 25 the lubricant for the respective bearings may be cleaned by filtration.

It is the object of our invention, further to provide novel lubricating means for the ram operating mechanism, comprising a lubricant 30 passage through which the lubricant moves upwardly for reaching an upper point of lubrication; further, to so arrange such passage that it moves with the rocker-arm for maintaining proper correlation between the outlet 35 of the lubricant passage and said upper point of lubrication; and, further, to provide novel lubricating passages at the supporting portion of the rocker-arm for passage of the lubricant therethrough.

It is the object of our invention, further, to provide such a rocker-arm with bearing 40 means, including novel lubricant passages, so that the lubricant passes through said bearing means during rocking movements of the rocker-arm; and, further, to provide novel lubricant passages for the link and articulations between the link and said rocker-arm and ram respectively.

The invention will be further readily understood from the following description and 50 claims, and from the drawings, in which latter:

Fig. 1 is a side elevation of our improved

device, partly broken away for better illustration of the parts.

Fig. 2 is an end elevation of the same, partly broken away, and partly in section on the irregular line 2—2 of Fig. 1.

Fig. 3 is a vertical section of the same, partly broken away, taken in the plane of the line 60 3—3 of Fig. 2.

Fig. 4 is a vertical cross-section of the same, taken in the plane of the line 4—4 of Fig. 1.

Fig. 5 is a vertical cross-section of a detail taken in the plane of the line 5—5 of Fig. 1.

Fig. 6 is a plan view of the link at the upper end of the rocker-arm and its connections, partly in axial section.

Fig. 7 is an enlarged axial section, showing the lubricant passages at the lower end of the 70 rocker-arm.

Fig. 8 is a cross-section of the same, taken in the plane of the line 8—8 of Fig. 7.

Fig. 9 is a horizontal section of my improved device, taken in the plane of the line 75 9—9 of Fig. 4.

Fig. 10 is a horizontal section of the primary distributing reservoir with the felt strainer removed, taken on the line 10—10 of Fig. 1.

Fig. 11 is a similar view of the secondary distributing reservoir, taken on the line 11—11 of Fig. 2.

Fig. 12 is a detail section of the pump, partly broken away, taken on the line 12—12 of 85 Fig. 1; and

Fig. 13 is a detail section taken on the line 13—13 of Fig. 1.

The frame 21 has a ram 22 reciprocating thereon, this ram in the present exemplification of mechanism being arranged to receive a tool which reciprocates crosswise of work supported for instance on a table adjustable on guides 23 on the frame in any ordinary or well-known manner. The frame has guides 90 24, 24', thereon, in which the ram reciprocates. These guides respectively have complemental horizontally disposed walls 26, 26', 27, 27', and complemental slanting walls 28, 28', 29, 29'. The walls 26, 26' and 28, 28' are 95 exemplified as relatively stationary, and the walls 27, 27', 29, 29', as located on the ram and reciprocating.

A rocker-arm 31 is pivoted to the frame and has articulation with the ram. Means are 105 provided for rocking the rocker-arm whereby

reciprocations are imparted to the ram. The articulation between the rocker-arm and the ram is exemplified as consisting of a link 32, having an articulation 33 with the rocker-arm and an articulation 34 with the ram.

This latter articulation is with a block 35, which comprises a nut having threaded connection with a screw-rod 36, journaled in the ram and arranged for having feed or positioning rotations imparted thereto for feeding or positioning the ram lengthwise. The block is arranged to be clamped to the ram, preferably at suitable positions lengthwise of the ram, for determining the paths lengthwise 10 of the ram in which the ram shall reciprocate. This clamping may be effected in any ordinary or well-known manner including, for instance, a clamping handle 37.

The rocker-arm is rocked by means of a 20 crank 41, on the bull-wheel 42, having a hub 43 journaled in a bearing 44 on the frame. The crank is on a crank-slide 45, adjustable in usual manner in radial direction on the bull-wheel toward and from the axis of the bull- 25 wheel for adjusting the lengths of stroke or angles of reciprocations of the rocker-arm. The crank is journaled in a crank-block 46 which has reciprocation in a guideway 47 in the rocker-arm, the crank-block having 30 slide connections with the walls of said guideway.

The bull-wheel comprises a gear 51. A pinion 52 meshes with the gear and is on a shaft 53 journaled in bearings 54, 55, in the frame. 35 This shaft and the bull-wheel are driven members. The shaft 53 has various speeds imparted thereto by driving gearing which comprises suitable speed changing mechanism communicating with gearing on the 40 shaft 53 for imparting various selective speeds to the shaft 53 and thereby reciprocating the rocker-arm at different speeds. This speed changing mechanism may comprise suitable gearing on shafts 56, 57, 58, journaled in bearings in a housing 59, shown as a 45 bulge in the frame.

The shaft 56 is exemplified as journaled in bearings 61, 62, 63, in the housing. The shaft 57 is shown journaled in said bearing 64, 65, 50 and the shaft 58 is shown journaled in bearings 66, 67, 68, in said housing. Some of these bearings are shown as ball bearings, others as roller bearings, but in form they may be any suitable bearings for permitting the 55 shafts to rotate therein. The shaft 58 is shown as having a pulley 69 thereon for receiving rotation from a suitable electric motor or other device.

The speed changing gearing may be of any 60 suitable form and arrangement and provided with any suitable control means, and may comprise gears indicated generally at 70 received about said respective shafts 56, 57, 58.

The exemplified means for lubricating the 65 various bearings and journals therein and the

complemental moving parts will now be described.

An initial primary reservoir 71 is provided. It is shown on a bracket 72 secured to the frame. This bracket is hollow, exemplified by the bore 73 therein, which registers with an opening 74 in the side of the frame. The reservoir has a bottom 75, in which there are holes 76, with which the upper ends of pipes connect in suitable manner for receiving lubricant from said reservoir. These holes are shown opening into grooves 77 in the bottom of the reservoir, forming ribs between said grooves.

A filtering pad 78 is received in said reservoir upon said bottom for causing the lubricant, for instance oil, to first pass through said filtering pad and thereby purify the oil before it is delivered to said holes. The elevations, exemplified by the ribs, raise the filtering pad above the bottoms of the depressions, exemplified as the grooves, for forming lubricant spaces between said pads and the lubricant passages.

A cover 81 is received over said reservoir and may, if desired, have a tight joint therewith for sealing said reservoir in order that pressure may be maintained on the oil therein, if desired, although our invention contemplates that the lubricant may be fed to the 95 various points of application by gravity. When it is desired to clamp the cover upon the reservoir, bolts 82 threaded to the wall of the reservoir and passing through the cover may be employed. The sides of the reservoir 100 may be provided with sights 83, which may be of glass, suitably fastened in the sides of the reservoir, for observation of the height of the oil in the reservoir.

The wall 27 is provided with a recess 85 with which a lateral passage 86 in the ram communicates. The wall 29 is provided with a groove 87, which extends lengthwise of the ram and with which said lateral passage communicates. An absorbent pad 88 is received in said recess, and is arranged to wipe upon the wall 26 for lubricating complementary walls 26, 27.

A lateral passage 89 communicates with said groove at various points along said groove during the reciprocating movements of the ram.

The wall 28 is provided with recesses 91, 92, in which absorbent pads 93, 94, are received. A lateral passage 95 communicates with each of said last-named recesses. There are similar structures at the other side of the ram designated by similar but primed reference numerals. A pipe 96 extends from the primary reservoir to each of the lateral passages, there being three of these pipes for the three lateral passages exemplified at one side of the ram. Similar pipes 96' extend from the primary reservoir and communicate with the lateral passages at the other side of the 120 125 130

rain, there being also three of these pipes exemplified. These pipes are connected in suitable manner with the holes in the bottom of the primary reservoir.

5 The latter pipes cross the path of the reciprocating rocker-arm in the form of loops 97.

The reservoir is located above the guides between the ram and the frame so that the lubricant in the reservoir may, if desired, 10 reach the point of lubrication by gravity.

Pipes 101, 102, extend from holes in the bottom of said reservoir through the opening 74, and are received at their other ends in holes 103, 104, in the bearings 54, 55, of 15 the shaft 53 for lubricating said bearings. The bearings may be provided with narrow longitudinal slits 105, 106, for respectively receiving the oil and distributing the same lengthwise of the journal and permitting 20 drainage of oil from the bearings into the interior of the machine. All the bearings are preferably provided with such slits, some of the slits being shown.

A pipe 109 is connected with one of the 25 holes in the bottom of the primary reservoir and leads to the bearing 44 for the hub 43 of the bull-wheel. This bearing comprises a suitable bushing. The pipe 109 is received in a hole 110 in said bearing. This hole communicates with the journal of the bull-wheel for lubricating said journal in said bearing. The oil received in said respective bearings lubricates said respective bearings and the 35 journals therein, the excess or used oil passing from said bearings into the interior of the frame.

A further pipe 111, shown as a larger pipe, has suitable connection with one of the holes in the bottom of the primary reservoir and 40 leads to the bearing means at the lower end of the rocker-arm.

In the present exemplification this bearing means comprises a bearing 112 in the frame. A bearing bushing 113 is received in said 45 bearing. This bushing is fixed in the bearing, as by means of a set bolt 114. The axle 115 of the rocker-arm is fixed in a bearing 119 of the rocker-arm, as by means of a set-bolt 116, and rocks with the rocker-arm, rocking 50 in the bushing 113. The axle is provided with a central bore 117 extending into one end of said axle. The bushing is provided with a bore 118 extending lengthwise thereof. A section of the pipe 111 is threaded in a 55 peripheral hole 120 in the bushing, this hole communicating with the bore 118.

A cap 121 is secured to the end of the bushing in manner to prevent oil leakage, as by screws 122. This cap is provided with a 60 radial bore or passage 123, which communicates with the longitudinal passage 118, and has its outer end closed, as by means of a plug 124. A pipe 125 is threaded in axial position in the cap, as at 126, and communicates 65 with the cross-passage 123. This pipe ex-

tends into the bore 117 in the axle, and has an oil-tight connection therewith, as by means of a packing 127, received in a recess 128 in the end of the axle, which packing is arranged to be compressed by means of a gland 70 129, threaded in the outer end of said recess.

A lubricant passage, shown as a pipe 131, extends lengthwise of the rocker-arm and connects with the axial bore in the axle, as by means of being threaded in a lateral hole 75 132 in said axle and passing through a hole 133 in the bearing 119 of the rocker-arm.

The pipe 131 extends lengthwise of the rocker-arm, suitable couplings, as at 134, being interposed therein between the section 80 of said pipe which is threaded into the axle and the section thereof which extends upwardly.

The upper end of this pipe is provided with a lateral projection 135 terminating in a 85 downward spout 136 above the link 32.

The lubricant passes from the reservoir 71 through the passage 111 into the lengthwise bore 118, thence into the transverse passage 123, thence through the pipe 125 into 90 the central bore 117 in the axle, leakage from the latter bore being prevented by the compressible packing 127. The lubricant then passes upwardly through the pipe 131, and is discharged from said pipe or passage to the 95 articulations at the upper end of the rocker-arm.

Lubricant pipes 141, 141', extend from holes in the bottom of the reservoir. The pipe 141 is connected at its lower end with a 100 hole 142, which extends through the bearing 112 and the bushing 113, for lubricating the axle in said bushing. The other end of the axle is received in a bushing 143, fixed in a bearing 144 by means of a set-bolt 145. A 105 lubricating hole 146 is in said bearing and said bushing. The lower end of the pipe or passage 141' communicates with the hole 146. The bushings 113, 143, are provided with 110 suitable slits for distributing the oil and discharging the spent oil into the interior of the frame.

The link 32 is provided with a recess 151, which forms a small oil recess, and which is shown extending crosswise of the link. The 115 link is provided with a fork 152 at one end, the tines of which have bearings 153, between which a central bearing 154 at the upper end of the rocker-arm is received. The link at its other end is provided with a central bearing 155, at the respective ends of which bearings 156 on the tines of a fork 157 on the block 35 are located. The journal pin 33 is received in the bearings 153, 154, and is fixed 120 in the bearings 153 on the link, as by means of a pin 158. The journal pin 34 is received in the bearings 155, 156, and is fixed in the bearing 155 of the link, as by a pin 159. A 125 passage 161 extends from the oil recess in the link lengthwise of the fork of the link 130.

and into the pin 33, and has a continuation 162, in the journal pin 33. This continuation extends axially in the pin and has a lateral offset which opens at the journal face of the bearing 154.

6 A lubricant passage 165 extends from the lubricant recess in the link in the opposite direction lengthwise of the link, and registers with a passage in the journal pin 34, the pin 10 having an axial passage 166 therein, with which the last-named passage communicates, the passage 166 having branches extending therefrom and opening at the journal faces of the bearings 156.

15 The passage 162 in the journal pin 33 has a laterally extending branch 167, which communicates with a groove 168 below said pin in the upper bearing 154 of the rocker-arm. This groove continues as a groove 169 on the 20 loop 170 of the rocker-arm, for receiving oil from the oil recess 151 in the link into a lubricant recess 171 at the side of said loop on said rocker-arm. A lubricant passage 172 extends from said recess, through which the 25 oil passes and drips into an oil-recess 174 in the upper end of the crank-block 46. The lower end of this oil-recess has a hole 175, which communicates with the journal face in the bearing in the crank-block. Filter pads 30 176 are located in slots in the side edges of the crank-block, holes 177 communicating therewith from the oil-recess 174. These filter pads contact with the slideway in which the crank-block reciprocates for lubricating 35 the same.

An inflow pipe 181 communicates with a pump 182, and is connected with a passage 183 in the primary reservoir. An out-flow pipe 184 is connected with an out-flow passage 185 in said reservoir, and with a hole 186 in a secondary lubricant reservoir 187, shown 40 located above the driving gearing. The inlet opening and the out-flow opening in the primary reservoir are preferably so related as 45 to maintain a body of lubricant in the primary reservoir for feeding the same to the various points of lubricant supplied thereby. The height of this body of lubricant may be observed through the sights 83.

50 It is instanced that there is a gravity feed of the lubricant through the pipes supplied by the primary reservoir, and the passages which supply the rocker-arm and its connected parts with lubricant, is shown of 55 greater diameter than the passages supplying the respective bearings, for the reason that there is an up-flow of the lubricant from the bearing means at the lower end of the rocker-arm to the points of lubrication at the upper end of the rocker-arm, the lubricant flowing upwardly to these latter bearings, due to the weight of the lubricant in the primary reservoir and the down-flow passage, and the fact that the primary reservoir is located above 60 the level of the guideways for the ram, and 65

the oil seeking its level throughout the passages. The out-flow passage 184, 185, is also preferably of greater diameter than the individual feed pipes, as the lubricant for the secondary feeding reservoir, the bearings for 70 the drive shafts, and the lubricant collecting reservoir therebelow are supplied through this passage.

The secondary lubricant feeding reservoir 187 is provided with a suitable number of 75 holes 188 in its bottom, communicating respectively with cross-grooves 189, forming ribs 190, on which a filtering pad 191 rests, forming lubricant collecting spaces under said pad. The holes 188 have sets of pipes 80 connected therewith, which feed the lubricant to the bearings of the respective shafts 56, 57, 58.

Thus pipes 192^a, 192^b, 192^c, communicate with certain of the holes 188, the other ends 85 of said pipes having communication with holes 193^a, 193^b, 193^c, in the bearings 61, 62, 63, in which the driving shaft 56 is journaled. Pipes 194^a, 194^b, communicate with certain 90 of the holes 188, the other ends of the pipes being received in holes 195^a, 195^b, in the bearings 64, 65, of the driving shaft 57. Pipes 196^a, 196^b, 196^c, communicate with others of the holes 188. The other ends of said pipes 95 communicate with the bearings 66, 67, 68, of the shaft 58.

An out-flow pipe 201 is received in the secondary lubricant feeding reservoir for receiving oil therefrom and dripping the same 100 into the lubricant collecting reservoir 202 located below said driving gearing. The upper end of this lubricant passage is preferably at such height in the secondary lubricant feeding reservoir as to insure that a body of oil or lubricant is in the secondary lubricant 105 feeding reservoir. This reservoir is provided with a cover 204 which is removable. The supply of lubricant desired for lubricating the mechanism is preferably poured into said reservoir.

110 Lubricant pipes 205, 206, communicate with holes in the bottom of the secondary reservoir, the pipe 205 communicating with a hole 207 in a bearing 208. This bearing has a shaft 209 therein, which is driven from the drive 115 shaft 58, as by means of spiral gears 210, 211. This shaft has a crank plate 212 fixed thereto, with the crank 213 of which a pitman 214 is articulated, the pitman having articulation 215 with a piston rod 216 of the pump 182. The pipe 206 opens above the crank plate for 120 feeding lubricant to said articulations.

125 The pump, as instanced, comprises a piston 221 on said piston rod 216, which reciprocates in a cylinder 222, a suitable packing 223 being received about said piston rod. The pump has an in-feeding port 225 and an out-feeding port 226, with which the inflow pipe 181 connects. A sieve 227 is received about said inlet port. Valves 228, 229, are arranged to 130

be respectively seated upon valve seats 230, 231, in alternate order, upon reciprocation of the piston, for causing flow of oil through the pump to the primary reservoir.

5 An out-flow passage 235 communicates with the primary collecting reservoir, a wall 236 surrounding said passage for determining the level of lubricant in said collecting reservoir and supplying a body 237 of lubricant 70 therein, into which drive gears which are on the shaft 58 are arranged to dip for feeding lubricant to the various gears.

10 The over-flow from the lubricant collecting reservoir 202 is arranged to pass through said 15 out-flow passage and to be received in a lower collecting reservoir 238, this lower collecting reservoir having a depression 239 therein, in which the in-feeding port 225 of the pump is arranged to be located. The pump is shown 20 supported by a bracket 240 extending from the frame.

15 In order to control the flow of lubricant from the primary lubricant feeding reservoir 71 to the various points of lubrication served thereby and to the secondary lubricant feeding reservoir, I prefer to provide regulating 25 means in the passage between said lubricant feeding reservoirs, instanced as a valve 243 having a handle 244, which is accessible from 30 the outside of the machine for regulating the lubricant passing to the secondary feeding reservoir, in order to insure that all of the lubricating points supplied by the primary lubricant feeding reservoir have sufficient 35 lubricant. This lubricant controlling means is especially useful when a force feed is provided for the primary lubricant feeding reservoir.

40 In our improved device the lubricant is pumped from the lower collecting reservoir to the primary feeding reservoir. The lubricant passes thence to the bearing means at the lower end of the rocker-arm, and thence upwardly to the articulating means at the upper 45 end of the rocker-arm. Lubricant also passes through the passages supplied from the primary feeding reservoir to the ram-slide and to bearings of the shafts of the driven gearing.

50 All of the lubricant thus fed is first filtered in said primary reservoir. The primary lubricant feeding reservoir is preferably located at a high point so that the feeding of the lubricant may be by gravity if desired. 55 It is elective however that the lubricant from the primary reservoir may be fed under pressure supplied by closing said primary reservoir and feeding the oil thereinto under pressure.

60 The surplus lubricant passes from the primary lubricant reservoir through the passage 184 into the secondary lubricant feeding reservoir. From the secondary lubricant feeding reservoir the lubricant passes to the 65 respective bearings for the driving gearing

preferably including speed changing gearing and to the pump mechanism. This lubricant is also preferably first filtered before entering the lubricant passages. A body of lubricant is insured in this secondary lubricant reservoir by the height of the opening of the out-flow or over-flow passage therein, through which the surplus lubricant passes to the lubricant collecting reservoir under the driving gearing, a portion of which driving 70 gearing is arranged to dip into said collecting reservoir for further lubricating the gearing.

75 The lubricant is fed from the secondary lubricant feeding reservoir preferably by gravity, but if desired, it may be fed under pressure by maintaining a pressure in said secondary feeding reservoir, the pressure being obtained by firmly clamping the cover upon 80 said reservoir and by the entrance of lubricant under pressure thereinto from the primary reservoir.

85 The surplus oil from the primary collecting reservoir is arranged to overflow into the lower lubricant reservoir, from which the oil is again pumped to the primary lubricant 90 feeding reservoir.

95 The lubricant may be detained in pockets in the bearings and drain thence into the lubricant collecting reservoirs.

Having thus fully described our invention, 100 what we claim as new, and desire to secure by Letters Patent, is:

1. In a device of the character described, the combination of a frame, a ram reciprocable thereon, guides between said frame and said ram, driven gearing for reciprocating said ram, bearings therefor, driving gearing including speed changing gearing for the latter, bearings therefor, a primary lubricant feeding reservoir, a secondary lubricant feeding reservoir, a lubricant collecting reservoir under the latter, and a lower lubricant collecting reservoir, lubricant passages from said primary lubricant feeding reservoir to said guides and to said first-named bearings, an outflow lubricant passage from said primary lubricant feeding reservoir for said secondary lubricant feeding reservoir, lubricant passages from said secondary lubricant feeding reservoir to said second-named bearings, 110 an outflow lubricant passage from said secondary lubricant feeding reservoir for said first-named lubricant collecting reservoir, a portion of said driving gearing dipping into said first-named lubricant collecting reservoir, an outflow passage from said first-named lubricant collecting reservoir for said second-named lubricant collecting reservoir, a pump for said lower lubricant collecting reservoir, and a lubricant passage between said pump 120 and said primary lubricant feeding reservoir 125

for returning lubricant from said lower lubricant collecting reservoir to said primary lubricant feeding reservoir.

2. In lubricating means of the character described, the combination of a lubricant collecting reservoir, a lubricant feeding reservoir, provided with a bottom having raised projections and depressions therebetween, a liquid lubricant filtering pad in said lubricant feeding reservoir on said projections to form spaces therebelow, lubricant feeding passages having openings in said depressions for receiving filtered liquid lubricant from said spaces, said lubricant feeding reservoir arranged for locating a body of liquid lubricant in said lubricant feeding reservoir above said filtering pad for being filtered through said filtering pad into said spaces, and an inflow lubricant passage and an outflow lubricant passage communicating with said lubricant feeding reservoir above said filtering pad, said outflow lubricant passage receiving excess unfiltered lubricant from said lubricant feeding reservoir and communicating with said lubricant collecting reservoir, and means for returning unfiltered lubricant from said lubricant collecting reservoir through said inflow lubricant passage to said lubricant feeding reservoir.
3. In a device of the character described, the combination of a frame, a ram reciprocable thereon, a rocker-arm, a link, an upper bearing between the upper end of said rocker-arm and said ram, a lubricant passage for said upper bearing extending upwardly lengthwise of said rocker-arm, and lubricant feeding means communicating with the lower end of said lubricant passage, and the upper end of said lubricant passage discharging lubricant for said upper bearing.

4. In a device of the character described, the combination of a frame, a ram reciprocable thereon, a rocker-arm, a bearing therefor at its lower end, a link, bearings between said link and the upper end of said rocker-arm and said ram respectively, and a lubricant passage for said last-named bearings by-passing said first-named bearing and extending lengthwise of said rocker-arm through which latter portion the lubricant moves upwardly.

5. In a device of the character described, the combination of a frame, a ram reciprocable thereon, a rocker-arm, a bearing therefor at its lower end, a link, bearings between said link and the upper end of said rocker-arm and said ram respectively, a lubricant container, and lubricant passages between said lubricant container and said last-named bearings including a passage which by-passes said first-named bearing and extends upwardly lengthwise of said rocker-arm through which upwardly extending portion the lubricant moves upwardly.

6. In a device of the character described, the combination of a frame, a ram having guide connection therewith, a rocker-arm, lower bearing means therefor for pivoting said rocker-arm, a link between the upper end of said rocker-arm and said ram, upper bearing means therefor, a lubricant container, and lubricant passages between said lubricant container and said upper bearing means extending through said lower bearing means and thence upwardly to said upper bearing means.

7. In a device of the character described, the combination of a frame, a ram having guide connection therewith, a rocker-arm, a lower bearing for the lower end of said rocker-arm, a crank-block having slide connection with said rocker-arm, a crank therein, upper bearing means between the upper end of said rocker-arm and said ram, a lubricant container, and lubricant passages therefrom through said lower bearing to said upper bearing means, arranged for upward passage of the lubricant between said lower bearing and said upper bearing means, and lubricant guiding means for gravity feed of the lubricant between said upper bearing means and said slide connection and said crank.

8. In a device of the character described, the combination of a frame, a ram having guide connection therewith, means for reciprocating said ram on said frame comprising a rocker-arm, a link, bearings at the respective ends of said link articulating said link respectively with the upper end of said rocker-arm and said ram, said link provided with a lubricant depression, and lubricant passages between said depression and said bearings, and said link arranged to be tilted with its respective ends alternately uppermost during reciprocations of said ram for feeding lubricant from said depression to said respective bearings.

9. In a device of the character described, the combination of a frame, a ram having guide connection therewith, means for reciprocating said ram on said frame comprising a rocker-arm, a link, bearings at the respective ends of said link articulating said link respectively with the upper end of said rocker-arm and said ram, said link provided with a lubricant depression, and a lubricant passage arranged for upward passage of the lubricant therethrough and discharge therefrom into said lubricant depression and lubricant channels from said depression to said respective bearings.

10. In a device of the character described, the combination of a frame, a ram having guide connection therewith, means for reciprocating said ram on said frame comprising a rocker-arm, a lower bearing therefor, a link, bearings at the respective ends of said link articulating said link respectively with the upper end of said rocker-arm and said

ram, said link provided with a lubricant depression between said last-named bearings, a lubricant container, a lubricant passage between said lubricant container and said lower bearing, a lubricant passage between said lower bearing and said link arranged for upward passage of the lubricant therethrough and discharge therefrom into said lubricant depression, and oppositely extending lubricant channels from said depression to said second-named bearings.

11. In a device of the character described, the combination of a frame, a ram having a guide connection therewith, a rocker-arm, a lower bearing thereon and rocking therewith, an axle fast therein, a coaxial stationary bearing on said frame therefor, articulating connection between the upper end of said rocker-arm and said ram for reciprocating said ram, a lubricant container, lubricant bores in said stationary bearing and in said axle coaxially arranged, a lubricant passage between said container and said bore in said stationary bearing, and a lubricant passage between said bore in said axle and said articulating connection in which the lubricant has an upward course.

12. In a device of the character described, the combination of a frame, a ram having a guide connection therewith, a rocker-arm, a lower bearing thereon and rocking therewith, an axle fast therein, a coaxial stationary bearing on said frame therefor, articulating connection between the upper end of said rocker-arm and said ram for reciprocating said ram, a lubricant container, a lubricant pipe in said stationary bearing, a lubricant bore in which said pipe is received, lubricant arresting

means in said bore about said pipe, a lubricant passage between said container and said pipe, and a lubricant passage connecting with said bore through said first-named bearing and extending upwardly along said rocker-arm to said articulating connection, and constructed and arranged whereby the lubricant has an upward course in said last-named lubricant passage.

13. In a device of the character described, the combination of a frame, a ram reciprocable thereon, driven gearing for operating said ram, bearings therefor, driving gearing for operating said driven gearing, bearings therefor, primary lubricant feeding reservoir, a secondary lubricant feeding reservoir, a set of lubricant feeding passages from said primary lubricant feeding reservoir to said first-named bearings, a set of lubricant feeding passages from said secondary lubricant feeding reservoir to said second-named bearings, filtering means at the entrances to said respective sets of lubricant feeding passages, an outflow passage for each of said reservoirs alongside the filtering means therein, said outflow passage for said first-named reservoir communicating with said secondary reservoir, a lower reservoir fed by said outflow passage of said secondary reservoir, a pump for the lubricant received in said lower reservoir, and a lubricant passage between said pump and said first-named reservoir, and arranged whereby filtered oil is fed to each of said bearings.

In testimony whereof, we have hereunto signed our names.

AUGUSTUS M. SOSA.
HANS BAERBALCK.

DISCLAIMER

1,699,816.—*Augustus M. Sosa and Hans Baerbalck*, Cincinnati, Ohio. LUBRICATING DEVICE. Patent dated January 22, 1929. Disclaimer filed October 18, 1929, by the assignee, *The American Tool Works Co.*

Hereby enters this disclaimer to that part of the claim in said specification which is in the following words, to wit:

“3. In a device of the character described, the combination of a frame, a ram reciprocable thereon, a rocker-arm, a link, an upper bearing between the upper end of said rocker-arm and said ram, a lubricant passage for said upper bearing extending upwardly lengthwise of said rocker-arm, and lubricant feeding means communicating with the lower end of said lubricant passage, and the upper end of said lubricant passage discharging lubricant for said upper bearing.”

Except when said claim 3 is limited as follows:

When the element in said claim of “lubricant feeding means” is limited to include a lubricant reservoir, lubricant supply means therefor, and a continuous unidirectional lubricant feeding passage from said lubricant reservoir to the lower end of said lubricant passage recited in said claim, said lubricant reservoir located as high as said upper bearing recited in said claim, and arranged that said lubricant reservoir during operation of the machine continuously receives lubricant by means of said lubricant supply means and simultaneously continuously feeds lubricant through said continuous unidirectional lubricant feeding passage by gravity to said lower end of said lubricant passage recited in said claim.

And your petitioner further hereby enters this disclaimer to that part of the claim in said specification which is in the following words, to wit:

“7. In a device of the character described, the combination of a frame, a ram having guide connection therewith, a rocker-arm, a lower bearing for the lower end of said rocker-arm, a crank-block having slide connection with said rocker-arm, a crank therein, upper bearing means between the upper end of said rocker-arm and said ram, a lubricant container, and lubricant passages therefrom through said lower bearing to said upper bearing means, arranged for upward passage of the lubricant between said lower bearing and said upper bearing means, and lubricant guiding means for gravity feed of the lubricant between said upper bearing means and said slide connection and said crank.”

Except when said claim 7 is limited as follows:

When the “lubricant container” referred to in said claim is limited to a lubricant container which is located as high as said upper bearing means recited in said claim, lubricant supply means are provided therefor, and said lubricant passages recited in said claim include a continuous unidirectional lubricant feeding passage from said lubricant container to said lower bearing recited in said claim, and arranged that during operation of the machine said lubricant container continuously receives lubricant from said lubricant supply means, and said lubricant container simultaneously continuously feeds lubricant by gravity through said lubricant passages recited in said claim, including said continuous unidirectional lubricant feeding passage, to said upper bearing means recited in said claim.

[Official Gazette November 12, 1929.]
